United States Patent Office

Des. 181,469
Patented Nov. 19, 1957

181,469

FIGURE TRUNDLE TOY OR SIMILAR ARTICLE

Marvin I. Glass, Chicago, Ill.

Application January 30, 1957, Serial No. 44,661

Term of patent 14 years

(Cl. D34—15)

Fig. 1 is a front perspective view of a figure trundle toy or similar article, showing my new design;

Fig. 2 is a front elevational view thereof; and

Fig. 3 is a rear perspective view thereof.

The dominant features of my new design are shown in solid lines in the drawing.

I claim:

The ornamental design for a figure trundle toy or similar article, substantially as shown and described.
